VENETIAN BLIND

Harry E. Condron, Jr., Dayton, Ohio, assignor to
Allan McL. O'Leary, Dayton, Ohio

Application November 12, 1946, Serial No. 709,210

3 Claims. (Cl. 20—62)

1

This invention relates to shades for windows and other openings and more particularly to shades of the transverse slat type.

An object of this invention is to provide a shade of the transverse slat type wherein the slats are pivotally mounted for angular adjustment in unison and wherein one or more of the slats may be removed at will to thereby eliminate the use of webs for supporting the slats and cords for holding the slats in position and for raising and lowering the slats.

Another object of this invention is to provide a shade or blind of the transverse slat type, wherein in the mechanism for supporting the slats is permanently secured to the window frame, resulting in a low cost, economical and efficient shade.

Other objects and advantages reside in the construction of parts, the combination thereof and the mode of operation, as will become more apparent from the following description.

In the drawings, Figure 1 is a perspective view of a window frame provided with a shade or blind of the transverse slat type.

Figure 2 is an enlarged, fragmentary, perspective view taken substantially on the line 2—2 of Figure 1.

Figure 3 is another enlarged, fragmentary, perspective view taken substantially on the line 3—3 of Figure 1, with the slats removed.

Figure 4 is a cross sectional view taken substantially on the line 4—4 of Figure 3.

Figure 5 discloses a modification showing a corrugated slat.

Figure 6 discloses another modification showing a ribbed slat.

Referring to the drawings, the reference character 10 indicates a window frame provided with the jambs 12 and 14. The blind includes a pair of channel-like frame members 20 and 22. The channel member 20 is secured to the jamb 12 by a plurality of screws 24. The channel 22 is secured to the jamb 14 by a plurality of screws 26. Members 20 and 22 are provided with a plurality of equally spaced apertures 28.

The channel 20 has pivotally attached thereto a plurality of slotted brackets 30, each provided with a stop or limiting projection 32. The flanges 34 extend parallel to each other and are snugly seated over the ends of the transverse slats 36. The flanges 34 are preferably made from resilient material, so as to yieldably engage the ends of the slats 36, to frictionally hold the ends of the slats 36 in position.

Each of the slotted brackets 30 is pivotally at-

2

tached to an adjusting bar or link 40, interconnecting all of the brackets, so that if one bracket is adjusted about the pivot 42 attaching the bracket to the channel 20, all of the brackets are adjusted in unison through the same angular distance. In order to facilitate the adjustment of the slats, one of the brackets is provided with an extension 44, supporting a hand-grip handle 46, functioning as a lever for adjusting the angular position of the slats.

The end of each slat 36 opposite the bracket 30 is provided with a pintle or pivot 50, projecting into an aperture 28 in the channel 22, so as to be journaled therein. The angular relation of the slats may be adjusted, so as to admit more or less light. Instead of raising the lower slats, so as to provide an opening, any number of slats may be removed by slipping the ends of the slats 36 from the brackets 30. After the end of the slat clears the bracket 30, the pintle 50 may be pulled out of the aperture 28. By this arrangement, any size opening may be provided.

The shade may be sold in standard sizes. The channel members 20 and 22, being made from sheet metal, can easily be cut to the desired length, then secured in position by means of the screws 24 and 26. The adjusting bar or link 40 is also severed to length. The ends of the slats 36 projecting into the brackets 30 are then cut to proper length, so that the slats may fit the window opening. As may be clearly seen in Figure 2, the slats 36 are cut so as to be slightly shorter than the distance from the aperture in the channel member 22 to the bottom of the channel member 30 to permit removal of the slats. The slats are cut to such a length that they may be removed.

In the modification disclosed in Figure 5, a cross sectional view of a corrugated or fluted slat 60 has been shown. This may be made from sheet metal or plastic molding material, reenforced or stiffened by corrugations. The end 62 of the slat that projects into the bracket 30 is preferably flattened.

In the modification disclosed in Figure 6, the slat 70 has been provided with a longitudinal rib 72 terminating in spaced relation from the end 74 of the slat projecting into the bracket 30. The slats 60 and 70 have both been shown with flattened ends 62 and 74. For some installations, it may be found desirable not to flatten the ends; but to provide slots for the reception of the ends that are sufficiently wide to accommodate the width of the rib or ribs, as the case may be. Such a structure may be produced more economically

than the flattened ends, in that the slats may then be cut from continuous length strips. Various other shapes and contours of slats may be used.

In conventional blinds of the transverse slat type, the cleaning of the blinds presents a problem. Such blinds are very difficult to clean. Special brushes have been devised for cleaning the slats; but such brushes cannot pass through the cords and cannot effectively clean around the webs. The shade disclosed herein can readily be cleaned by slipping the slats out of the brackets, so as to permit each of the slats to be washed, dusted or otherwise cleaned, and then replaced. There are no webs and no cords to be soiled. The slats are unobstructed from one end to the other.

Although the preferred embodiment of the device has been described, it will be understood that within the purview of this invention various changes may be made in the form, details, proportion and arrangement of parts, the combination thereof and mode of operation, which generally stated consist in a device capable of carrying out the objects set forth, as disclosed and defined in the appended claims.

Having thus described my invention, I claim:

1. A blind of the transverse slat type for a window opening, said blind including apertured channel members permanently secured to the jambs of the window frame, there being one channel member for each jamb, a plurality of equally spaced brackets pivotally mounted to one of the channel members, each of said brackets including a pair of parallel flanges directed in planes normal to the longitudinal axis of the channel members, a stop projecting outwardly from the bracket adjacent the ends of the flanges, means for interconnecting the brackets so as to cause the brackets to be adjusted in unison, and a plurality of slats slightly shorter than the distance from the portion of the brackets between the flanges to the aperture in the channel member mounted on the opposite side of the window frame, each of said slats being provided with a pintle in one end, said pintles being journaled in the apertures in the channel member opposite the brackets, the other ends of the slats being removably mounted between the flanges of the brackets and normally in contact with the stop, a vacant area in the blind being provided by removing some of the slats.

2. A blind of the transverse slat type for a window opening, said blind including apertured channel members permanently secured to the jambs of the window frame, there being one channel member for each jamb, a plurality of equally spaced brackets pivotally mounted to one

of the channel members, each of said brackets including a pair of parallel flanges directed in planes normal to the longitudinal axis of the channel members, means for interconnecting the brackets so as to cause the brackets to be adjusted in unison, one of the brackets terminating in a handle for oscillating the bracket and with it the other brackets in unison, and a plurality of slats slightly shorter than the distance from the portion of the brackets between the flanges to the aperture in the channel member on the opposite side of the window frame, each of said slats being provided with a pintle in one end, said pintles being journaled in the apertures in the channel member opposite the brackets, the other ends of the slats being removably mounted between the flanges of the brackets, a vacant area in the blind being provided by removing some of the slats.

20 3. A blind of the transverse slat type for a window opening, said blind including apertured strips permanently secured to the jambs of the window frame, there being one strip for each jamb, a plurality of equally spaced brackets pivotally mounted to one of the strips, each of said brackets including a pair of parallel flanges directed in planes normal to the longitudinal axis of the strips, a stop projecting outwardly from the bracket adjacent the ends of the flanges, means 25 for interconnecting the brackets so as to cause the brackets to be adjusted in unison, and a plurality of slats slightly shorter than the distance from the portion of the brackets between the flanges to the aperture in the channel member 30 on the opposite side of the window frame, each of said slats being provided with a pintle in one end, said pintles being journaled in the apertures in the strip opposite the brackets, the other ends of the slats being removably mounted between the flanges of the brackets and normally in contact with the stop, a vacant area in the blind being provided by removing some of the slats.
